UNITED STATES PATENT OFFICE

93,164

DESIGN FOR A ROD HAND-LINE BLOCK FOR FISHERMEN

Samuel M. Hauser, Jackson Heights, N. Y.

Application April 24, 1934, Serial No. 51,497

Term of patent 3½ years

To all whom it may concern:

Be it known that I, SAMUEL M. HAUSER, a citizen of the United States, residing at Jackson Heights, in the county of Queens and State of New York, have invented a new, original, and ornamental Design for a Rod Hand-Line Block for Fishermen, of which the following is a specification, reference being had to the accompanying drawing, forming a part thereof.

The figure is a perspective view of a rod hand-line block for fishermen, showing my design.

I claim:

The ornamental design for a rod hand-line block for fishermen, as shown.

SAMUEL M. HAUSER.
